E. R. BURTNETT

INTERNAL COMBUSTION ENGINE

Original Filed Oct. 2, 1922

Inventor
Everett R. Burtnett
By Martin P. Smith
Atty.

UNITED STATES PATENT OFFICE.

EVERETT R. BURTNELL, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Original application filed October 2, 1922, Serial No 591,761. Divided and this application filed September 13, 1923. Serial No. 662,415.

To all whom it may concern:

Be it known that I, EVERETT R. BURTNELL, a citizen of the United States, residing at Los Angeles, in the county of Los Angeles and State of California, have invented certain new and useful Improvements in Internal-Combustion Engines, of which the following is a specification.

My invention relates generally to internal combustion engines and more particularly to cylinder heads for the sleeve valve types of engines, the principal objects of my invention being, to provide a head that is of relatively simple, strong and durable structure; to arrange in the head, a poppet valve that controls the admission of gaseous fuel into the cylinder on which the head is located; to construct the head with an ignition chamber or pocket that is in direct communication with the port that is controlled by the gaseous fuel inlet valve; to provide the head with an integral portion that extends inwardly into the cylinder and cooperates with the latter in providing bearings for the upper inner portion of the sleeve valve and, further, to form in said inwardly extending portion, an elongated tapered chamber that communicates directly with the ignition pocket and performs the functions of a charge compression, charge combustion, and expansion chamber.

This application is a division of the application Serial No. 591,761 filed by me, October 2nd, 1922, for internal combustion engines.

With the foregoing and other objects in view, my invention consists in certain novel features of construction and arrangement of parts, that will be hereinafter more fully described and claimed and illustrated in the accompanying drawings in which:-

Fig. 1 is a vertical section taken through the center of a sleeve valve engine cylinder, having a head of my improved construction.

Fig. 2 is a cross section taken on the line 2—2 of Fig. 1.

Fig. 3 is a side elevational view of my improved cylinder head.

Fig. 4 is an elevational view looking at the inner end of the head.

Referring by numerals to the accompanying drawings which illustrate a practical embodiment of my invention, 10 designates

an engine cylinder, the upper portion of which is provided with a chamber 11, through which may be circulated, a suitable fluid cooling medium, preferably water. Arranged for reciprocatory movement within said cylinder is a sleeve valve 12, and arranged for reciprocatory movement within the latter is a piston 13.

Secured in any suitable manner upon the head end of cylinder 10 is a head block 14 having a chamber 15 that is in communication with chamber 11.

Formed integral with and projecting from block 14 into the chamber within cylinder 10, is a concentrically arranged, hollow, cylindrical head 16, the external diameter of which is slightly less than the internal diameter of the chamber within said cylinder.

This arrangement provides a relatively narrow annular space between the cylinder wall and the outer wall of the head 16 and this space provides a working chamber for the upper portion of the sleeve valve 12.

Seated in the outer surface of the lower portion of head 16 is a relatively wide packing or junk ring or rings 18, the same serving to provide a leak proof joint between the head and sleeve valve. Head 16 is formed with inner and outer walls that are spaced apart to form a cooling fluid circulating chamber 19 that communicates directly with chamber 15 and the inner wall of said head is substantially bell shaped so that the space or chamber 20 that is enclosed by said inner wall gradually tapers toward its upper end.

This chamber, which serves as a charge compression, combustion and expansion chamber communicates at its upper end, directly with an ignition pocket 21 that is formed in the center of block 14.

Seated in the central portion of block 14 directly above the pocket 21 is a cage 22 having a gaseous fuel inlet passageway, that is provided at its inner end with a valve seat, and normally resting upon the latter is a spring held gaseous fuel inlet valve 24.

This inlet valve may be operated in any suitable manner, preferably by means of a rocker arm 25 that is actuated by an eccentric controlled push rod 26.

Seated in block 14 to the side of the fuel

inlet valve, is a spark plug 27, the inner ends of the electrodes of which terminate within the ignition pocket 21.

It will be understood that the sleeve valve

5 12 controls the exhaust of products of combustion from the piston clearance chamber and the subsequent admission of an inert volume of air or cooled products of combustion.

10 After the inert volume has been admitted to the piston clearance chamber, inlet valve 24 is unseated to admit a precompressed charge of gaseous fuel and which latter is compressed in stratified relation within 15 pocket 21 above the inert volume that is compressed within chamber 20, the compression of this stratified charge, being effected by the upward stroke of piston 13.

As the piston passes high center or immediately thereafter, the compressed gaseous fuel charge is ignited by a spark produced between the terminals of the electrodes of spark plug 27 and the force of the expansion resulting from combustion, passes 25 downward through chamber 20 and impinges directly against the head of piston 13 to drive the same downward on its power stroke.

Inasmuch as the depending portion 16 of 30 the head is provided with a relatively large cooling fluid circulation chamber 19, the heat resulting from the combustion of gaseous fuel within the pocket 21 and chamber 20 is rapidly disseminated.

35 My improved cylinder head is of relatively simple structure, may be easily machined, extends downwardly into the cylinder chamber so as to provide a bearing for the inner surface of the upper portion of the 40 sleeve valve, and as the ignition pocket and the combined compression and combustion chamber are directly connected to each other and in direct axial alignment with the piston and piston clearance chamber, the efficiency of the engine is materially increased, 45 due to the practically straight unrestricted sweep of the expansive power from the ignited charge, into the clearance chamber and against the head of the piston therein.

50 Obviously, minor changes in the size, form and construction of the various parts of my improved cylinder head may be made

and substituted for those herein shown and described without departing from the spirit of the invention, the scope of which is set forth in the appended claims.

I claim as my invention:—

1. In an internal combustion engine, the combination, with a combustion cylinder and a sleeve valve arranged for operation therein, of an inverted cylinder head secured to said cylinder and extending downwardly into the upper portion of said sleeve valve, the lower portion of said cylinder head having a compression clearance chamber, the lower portion of which gradually enlarges to the same diameter as the internal diameter of the sleeve valve, the upper portion of said cylinder head having a charge localization pocket that communicates with the upper portion of the compression clearance chamber by a venturi passage, a centrally located poppet valve arranged in the upper portion of said head for admitting gaseous fuel into the charge localization chamber, and ignition means projecting into said charge localization pocket.

2. In an internal combustion engine, the combination, with a combustion cylinder and a sleeve valve arranged for operation therein, of an inverted cylinder head secured to said cylinder and extending downwardly into the upper portion of said sleeve valve, the lower portion of said cylinder head having a compression clearance chamber, the lower portion of which gradually enlarges to the same diameter as the internal diameter of the sleeve valve, the upper portion of said cylinder head having a charge localization pocket that communicates with the upper portion of the compression clearance chamber by a venturi passage, a centrally located poppet valve arranged in the upper portion of said head for admitting gaseous fuel into the charge localization chamber, ignition means projecting into said charge localization pocket, and said inverted cylinder head having a cooling fluid circulation chamber that entirely surrounds the compression clearance chamber and said charge localization chamber.

In testimony whereof I affix my signature:

EVERETT R. BURTNELL.
